Filed Feb. 15, 1963, Ser. No. 73,581

Term of patent 14 years

(Cl. D80—8)

Fig. 1.

Fig. 2.

Fig. 3.

The dominant features of my design reside in the portions shown in full lines, the broken line representation of hangers being for illustrative purposes only.

I claim:

The ornamental design for a clothing display rack or similar article, as shown and described.
